(57) **CLAIM**

I claim the ornamental design for a rod holder, as shown and described.

DESCRIPTION

FIG. 1 is a perspective view of a rod holder showing my new design;

FIG. 2 is a right-side elevation view thereof;

FIG. 3 is a left-side elevation view thereof;

FIG. 4 is a rear elevation view thereof, with the front elevation view being a mirror image thereof;

FIG. 5 is a front elevation thereof;

FIG. 6 is a top plan view thereof;

FIG. 7 is a bottom plan view thereof; and

FIG. 8 is a cross-sectional view shown along line 8-8 of FIG. 6;

FIG. 9 is a perspective view thereof with a fishing pole;

FIG. 10 is a perspective view thereof with an insulated can and a weld-mount bracket;

FIG. 11 is a perspective view thereof with a clamp; and,

FIG. 12 is a perspective view thereof with a transom bracket. The broken lines depicting a fishing pole, insulated can, weld-mount bracket, clamp, and transom bracket are included for the purposes of illustrating environmental structure and form no part of the claimed design.
